F. DUTCHER

RAILWAY SIGNAL TORPEDO

Filed April 14, 1924

Inventor
Frank Dutcher,
By A. Patterson

Attorney

UNITED STATES PATENT OFFICE.

FRANK DUTCHER, OF MCKEESPORT, PENNSYLVANIA.

RAILWAY SIGNAL TORPEDO.

Application filed April 14, 1924. Serial No. 706,359.

To all whom it may concern:

Be it known that I, FRANK DUTCHER, a citizen of the United States, residing at Versailles Boro., McKeesport, in the county 5 of Allegheny and State of Pennsylvania, have invented certain new and useful Improvements in Railway Signal Torpedoes, of which the following is a specification, reference being had therein to the accompanying drawing.

This invention relates to improvements in railway signal torpedoes, and it relates to improvements in clips for attaching the rail-engaging strap to the torpedo case.

The primary object of the present invention is to provide an improvement in clips, the construction being such that the clip is clamped by a projecting flange of the case, or strengthening ring.

A further object of the invention pertains to making the clip in the form of a disk, the disk being clamped by a projecting part of the torpedo case or ring.

Another object of the invention pertains 25 to making the clip in the form of a disk which is clamped by the action of a strengthening ring, the said disk and spring strap being so shaped that the strap is locked in position by the disk so that it cannot move endwise.

Further objects of the invention will appear from the following description.

In the accompanying drawings—

Figure 1 is a perspective view of the under 35 side of the torpedo showing the improved clip and spring strap attached thereto.

Fig. 2 is an enlarged transverse section of the torpedo with the clip and strap in position thereon.

Fig. 3 is an enlarged inverted plan view 40 showing a lead strap attached by means of the clip.

Figs. 4 and 5 are modifications of the invention.

The present invention is here shown applied to a circular torpedo. I do not, however, limit the invention to that shape, for the shape of the torpedo may be varied without departing from the spirit of my invention.

Referring now to the drawings in which the case, as shown, consists of two parts 1 and 2, which telescope each other. The formation, however, of the case may be varied without affecting the present im-

provement. Tightly embracing the outer member 1 of the case is a strengthening ring 3. This ring 3 and the case are constructed of paper or fiber making a non-flying torpedo.

The present invention embraces making the strengthening ring 3 wider than the case, whereby it projects as shown at 4. This makes the under side of the torpedo recessed, and in this recess is placed the 65 clip 5.

This clip in the form here shown comprises a disk, which has its central portion 6 bulged outward, thus forming a space between the bulged portion and the part 2 70 of the case. At the same time the bulged out portion forms an annular shoulder 7, and also forms an annular flat part 8, that engages directly the part 2 of the case. The part 8 tightly fits against the case as shown. 75

The said disk portion 5 is made of a size that it fits within the recesses and is tightly grasped at its periphery by the extending part 4 of the ring 3.

In assembling the torpedo, the clip is 80 placed in the ring before the case is applied. Then the forcing of the case in the ring causes the clip to be tightly grasped by the extending part of the ring, which holds the clip tightly and firmly in position.

This clip, as here shown, is constructed with a central opening 9, and oppositely located openings 10, through which openings the lead strap 11, when in use, passes as shown in Fig. 3.

This clip is especially adapted for uniting a two-part spring strap, and this is shown in Figs. 1 and 2. In these figures the two parts of the strap 12 have their upper ends pass through the said opening with their extremities 13 doubled around the parts 14 of the clip, as shown. Attention is directed to the fact that both parts of the spring strap are bent upward, as at 15, which bend 15 forms a lock in connection with the shoulder 7, whereby the two parts of the strap are locked in position when the clip is applied to the torpedo case.

Preferably, the two parts of the spring strap are bent in the shape here shown before it is applied, and the two parts of the strap are applied to the clip, before the clip is applied to the torpedo. The two parts of the strap after being bent are applied to the clip by passing the doubled ends through 110

the opening 10 to the opening 9, when an endwise pull snaps the strap in position on the clip. The bent parts 15 and shoulder 7 cause a snapping action of the strap, whereby the said strap is locked in the clip.

I desire it to be understood that modifications may be made in the construction here shown without departing from the said invention, one form of modification being 10 shown in Fig. 4. In this figure the modification consists in extending the outer wall of the part 1', and the clip placed under the bottom of the part 2 of the case, with its periphery in engagement with the extended 15 wall 1', of the part 1 of the case. When this construction is used, the clip will be placed on the torpedo case before the application of the strengthening rib 3. It will be understood that the projecting flange 1' of the 20 case is readily extended sufficiently to hold the clip in position thereon until the strengthening and clasping ring 3 is applied to the case, and when it is applied it forces the periphery of the disk into the flange, holding it tightly and firmly in position.

When using the expression that the torpedo has an extending flange in the claims, it will be understood as broad enough to 30 cover either the strengthening and clasping ring 3, or the extended part 1' of the case, unless the claim specifically defines the modified form.

Also the disk may be made in the modified form shown in Fig. 5, whereby, in which 35 case, the bulged portion 7 instead of being in annular form, will be in a hump or short form, as shown at 7' in Fig. 5. It will be understood that in the operation of locking the strap, it will have the same operation 40 as the annular shoulder.

In showing the modifications, I have not attempted to include what may occur to others skilled in the art, and, therefore, the 45 claims are broadly drawn to cover the said invention and modifications thereof.

Having thus described my invention, what I claim and desire to secure by Letters Patent is:—

1. An improved railway signal torpedo, 50 comprising a case having a flange extending from one side thereof, a clip held by the extended flange, said clip having therein strap openings, and a two-part strap passing through the said openings, the clip and

strap being bent for causing the strap to be 55 held in position on the clip.

2. An improved railway signal torpedo, comprising a case having a flange depending from its bottom, a clip held by the said flange, the clip having strap openings, a two-part spring strap passing through the said openings, and the strap and clip having interlocking bent portions, whereby the strap is held in position on the clip.

3. A railway signal torpedo, comprising 65 a case having a flange at its bottom, a clip extending across the case and held by the said flange, the clip having strap openings, and a two-part spring strap passed through the said openings, the strap and the clip having oppositely bent interlocking parts for holding the strap in position.

4. A railway signal torpedo, comprising 75 a case having an annular downwardly extending flange, of a disk-shaped clip fitting within the flange, the periphery of said disk biting into the inner wall of said flange thereby holding the clip in position, the clip having a strap opening, and a strap passing through the said opening.

5. An improved railway signal torpedo, comprising a case having a flange, a disk-shaped clip held to the torpedo by the said flange, the said disk having an outwardly 85 bulged portion forming a shoulder and strap openings, of a strap passing through said openings, the strap being bent to interlock with the bulged portion.

6. An improved railway signal torpedo, 90 comprising a case having a depending flange, a disk clip held by the said flange, the disk having its periphery flat and its center portion bulged outward, the bulged portion having strap openings, and a strap passing through the said openings, the said strap bent to interlock with the shoulder formed by the bulged portion of the clip.

7. An improved railway signal torpedo, 95 comprising a case having a strengthening ring surrounding its periphery, the said ring depending below the bottom of the case forming a clip holding member, a clip held by the depending portion of the ring, the clip having strap openings, and a strap passing through the said openings.

In testimony whereof I hereunto affix my signature.

FRANK DUTCHER.
